EVAPORATOR

Franklin G. Slagel, Buffalo, N. Y., assignor to
Fedders Manufacturing Company, Inc., Buffalo, N. Y., a corporation of New York

Application December 31, 1931, Serial No. 584,211

6 Claims. (Cl. 62—126)

This invention relates to mechanical refrigerating systems and more particularly to evaporators.

An object of my invention is to provide a new and novel form of sheet metal evaporator.

Another object of my invention is to provide a sheet metal evaporator which can be economically formed and assembled.

A further object of my invention is to provide a header and chamber forming housing which are associated in a novel manner to form a leak-proof refrigerant circulating system.

Still another object of my invention resides in forming a storage chamber with a housing having a plurality of refrigerant duct loops arranged in groups each having an individual connection with the header.

Other objects of the invention will appear from the following description taken in connection with the drawing, which forms a part of the specification, and in which:

Fig. 1 is a side elevational view of an evaporator incorporating my invention.

Fig. 2 is a sectional view of the same taken on line 2—2 of Fig. 1.

Fig. 3 is a plan view of the chamber forming housing with the header removed therefrom.

Fig. 4 is a fragmentary view of the manifold portion of the inner wall of the chamber forming housing.

Referring now to the drawing by characters of reference, 10 represents the header and 11 the chamber forming housing of an evaporator which is adapted to be connected in a circuit with a condenser and a compressor (not shown) in the conventional manner.

The header is constructed preferably of sheet metal and is in the form of a cylinder. The housing forming the storage chamber is also formed of sheet metal and consists preferably of only two sheets 12 and 13. The outer sheet of material is formed along two opposite ends with a pressed out rib 14 which forms manifolds, and extending normal to the manifolds are aligned pressed out ribs 15 and 16. Every three of such aligned ribs are grouped adjacent the central portion of the sheet and the ends of the aligned ribs terminate short of each other.

The inner sheet is substantially the same in outline as the outer sheet, however it is longer in one direction so that the ends 46 can be folded around the ends of the outer sheet of material and seam welded therewith, as indicated at 17. The inner sheet is formed with three depressed portions 18 to provide manifolds for the ends of

the groups of aligned ribs 15 and 16 formed in the outer sheet. The sheets are welded together, as indicated at 19, between the groups of ribs and between the individual ribs of each group, and the outer sheet is formed with outwardly projecting flaring necks 20 arranged centrally of the manifolds 18.

The sheets are arranged in parallel relation with the ribs, necks and depressed portions formed therewith, and with the ends overlapping the outer sheet in the other direction. The sheets are then welded together along their abutting surfaces, along the ribs 15 and 16 and then the ends 46 are folded around the adjacent ends of the outer sheet and seam welded the entire length. The sheets are also seam welded together along their entire length adjacent the overlapping edges, as indicated at 21. The sheets are next bent to form an open ended storage chamber which is preferably rectangular. The overlying edges of the sheets are associated to overlap and are spot welded together along their entire length, as indicated at 22.

The housing provides a storage chamber and a refrigerant duct means around the chamber. The ribs 15 and 16 substantially surround the chamber in spaced relation longitudinally thereof, and communicate with one of the manifolds 14 and with one of the manifolds 18. Groups of ducts communicate with each manifold 18 and the necks 20 provide connections between the manifolds 18 and the interior of the header.

The header is formed with three depending necks 24 into which the necks 20 telescope and the ends of the necks 20 are spun over the shoulders 40 in the header from which the necks 24 depend. The telescoping necks are tin dipped to provide leak proof joints. This spun relation of the necks with the shoulders form rigid connections between the header and the chamber housing.

The inner sheet 12 of the housing is formed with longitudinally extending beads 41 arranged in vertical spaced relation on opposite sides of the chamber for the purpose of providing parallel rails to support trays. These beads form longitudinally extending manifolds communicating with the ribs or ducts 15 and 16 so that the rails are thus directly exposed to refrigerant. Below the rear end of the rails, bosses 43 are pressed out from the inner sheet 12 and serve as stops for trays which are slid into the housing and supported on the rails.

The evaporator thus formed can be quickly

fabricated and assembled at a low cost. The refrigerant circulating system substantially surrounds the storage chamber and due to the manifolding will promote efficient heat transfer. It 5 will be understood that the evaporator is of the flooded type so that the manifolds and connecting ducts will always be filled with liquid refrigerant, and that the refrigerant moves into and from the housing through the telescoping necks.

10 Although this invention has been described in connection with certain specific embodiments, the principles involved are susceptible of numerous other applications readily conceived by persons skilled in the art, and the invention is therefore 15 to be limited only as indicated by the scope of the appended claims.

What I claim is:

1. An evaporator comprising a header, a chamber forming housing, said housing having a plurality of manifolds in the top wall and duct means 20 in the side walls leading from the manifolds, and connecting means between the header and the housing, said connecting means forming a communication between the interior of the header and 25 the manifolds.

2. An evaporator comprising a header having a plurality of depending necks, and sheet metal housing means forming a storage chamber having duct means substantially surrounding the same, 30 said housing having necks extending therefrom and communicating with the duct means, said housing necks telescoping into the header necks and being spun therein.

3. An evaporator comprising a header having a 35 plurality of spaced depending outlet necks, a housing having duct means therein, necks extending from the housing and telescoping the header necks, said housing necks communicating with the

duct means, and means securing the necks in leak proof relation.

4. In an evaporator for refrigerating systems, a pair of sheets of metal secured together and welded together around the edges, the inner sheet having spaced inwardly pressed portions forming manifolds, the outer sheet having parallel pressed out portions forming manifolds and spaced pressed out ribs communicating with one of the manifolds formed in the same sheet and one of the manifolds in the other sheet, necks pressed from the outer sheet communicating with the manifolds of the inner sheet, and a header with which the necks are fixed and communicate. 10

5. In an evaporator for refrigeration systems, a 15 header, a pair of sheets of metal secured together and bent to form a storage chamber, one of said sheets having pressed portions forming a plurality of ducts between said sheets, and the outer sheet having an outwardly extending neck portion communicating with said ducts, said neck portion being secured to said header and communicating therewith. 20

6. In an evaporator for refrigeration systems, a header, a pair of sheets of metal secured together and bent to form a rectilinear storage chamber, one of said sheets having pressed portions forming a plurality of spaced ducts between the sheets, said ducts having their extremities terminating in the upper and lower walls of the 30 rectilinear chamber, manifolds formed in one of the sheets and connecting the extremities of groups of ducts in the upper wall of the chamber, and protruding neck portions formed in one of the sheets and each communicating with a manifold, said neck portions being secured to said header and communicating therewith. 35

FRANKLIN G. SLAGEL.
